DESIGN FOR A GEM SETTING

William H. Rothe, Irvington, N. J.

Application May 4, 1934, Serial No. 51,686

Term of patent 7 years

To all whom it may concern:

Be it known that I, WILLIAM H. ROTHE, a citizen of the United States, residing at Irvington, in the county of Essex and State of New Jersey, have invented a new, original, and ornamental Design for a Gem Setting, of which the following is a specification, reference being had to the accompanying drawing, forming part thereof.

In said drawing, Fig. 1 is a side elevation, Fig.

2 is a top plan view, and Fig. 3 is a side elevation viewed toward a corner of the setting, the said views showing the gem setting according to my new design.

I claim:

The ornamental design for a gem setting, as shown.

WILLIAM H. ROTHE.
